UNITED STATES PATENT OFFICE.

WILLIAM E. DUTE, OF CLEVELAND, OHIO, ASSIGNOR TO HOFFMAN ARMS COMPANY, OF CLEVELAND, OHIO, A CORPORATION OF DELAWARE.

FIREARM.

Application filed February 15, 1924. Serial No. 692,967.

To all whom it may concern:

Be it known that I, WILLIAM E. DUTE, a citizen of the United States, residing at Cleveland, in the county of Cuyahoga and State of Ohio, have invented certain new and useful Improvements in Firearms, of which the following is a specification.

My invention relates to fire arms and particularly to repeating rifles of the bolt type, in which the cocking and loading and the ejecting of the empty shells is accomplished by movement of a bolt. Although it is applicable to various types of fire arms, it is particularly adapted to use, and is herein-after described, in connection with a repeating rifle of the Springfield type.

One object of my invention is to construct a fire arm of the class described, which is provided with a movable bolt adapted to be rotated from the left side of the gun.

Another object is to construct a repeating rifle provided with a pinion operated, rotatable bolt.

Another object is to construct a fire arm of the class described, provided with a rotatable bolt adapted to be rotated by a pinion disposed on the left side of the bolt.

A further object is to provide mechanism of simple character which is capable of use with existing types of fire arms, and which may be applied thereto at slight expense and with but few alterations to such guns, whereby the gun may be converted from one in which the bolt is operated from the right side to one in which the bolt is operated from the left side.

Other objects ancillary to the foregoing will be combined at and described more in detail hereinafter.

In the drawings attached to and forming a part of this specification:

Figure 1 is a fragmentary top plan view of a Springfield rifle provided with a bolt and other parts embodying my invention.

Figure 2 is a rear end elevation of the bolt and associated parts taken on line 2—2 of Figure 1.

Figure 3 is a fragmentary top plan view of the rear end of the bolt shown in Figure 1.

Figure 4 is a fragmentary right side elevation of the bolt shown in Figure 3.

Figure 5 is a fragmentary bottom plan view of the device shown in Figure 3.

Figure 6 is a fragmentary left side elevation of the device shown in Figure 3. 55

Figure 7 is a rear end elevation taken on line 7—7, Figure 3.

Figure 8 is a cross section taken on line 8—8, Figure 3. 60

In the attached drawings, I have shown a rifle of the Springfield type with the stock 1 and barrel 2 both broken away and the trigger and all other operating parts, except those to which my invention particularly pertains, omitted. It will be understood however that I contemplate providing a fire arm complete in all respects, and in this specification and the appended claims, I particularly desire it to be understood that a fire arm complete in all respects is employed unless otherwise specifically mentioned. 70

In the drawings, 1 indicates the stock and 2 the barrel of a rifle of the Springfield type; 3 designates a bolt receiver in which the bolt 4 is mounted for longitudinal and rotational movement. The forward end 3^a of the receiver is substantially cylindrical, as is also the rear end 3^b, the top and right side of the receiver being cut away as at 3^c to expose the bolt and the top of the magazine and to permit ejection of empty shells, as is well known by those skilled in the art. 75 On the left side of receiver 3, near the rear end thereof, are formed means for supporting a cut-off lever which, by suitably engaging the bolt, may cause the fire arm to be a single fire or repeating device. Preferably, this means of mounting the cut-off 80 lever consists of two projections 5 spaced apart, between which a cut-off lever 6 is movably mounted on the cut-off spindle 7. On a purpose later to be described, I preferably extend the spindle 7 through the rear projection 5, as shown. Projection 8 extends rearwardly from the top left side of the cylindrical portion 3^b of receiver 3 for a purpose which will hereinafter appear. 85

For a purpose later to be described, I preferably extend the spindle 7 through the rear projection 5, as shown. Projection 8 extends rearwardly from the top left side of the cylindrical portion 3^b of receiver 3 for a purpose which will hereinafter appear. 90

Receiver 3 is provided with a central longitudinal opening having the customary interior grooves for receiving the various lugs and projections on the bolt 4, and is adapted to permit longitudinal and rotational movement of the bolt with respect to the receiver. This bolt comprises the usual cylinder 9 with extractor 10, lugs 11 and 12, cocking piece 13, with its depending lug 14. 100

105

and safety lock 15. 16 indicates a breech bolt sleeve of new and improved form, which consists of a portion 16^a in which the cocking piece 13 is movable and on which 5 the safety lock is mounted, as is the usual practice. The sleeve 16 is provided with a slot in its bottom wall of sufficient size to receive slidably the lug 14 on cocking piece 13. The sleeve 16 is provided on 10 the left side with means for mounting a pinion to engage with the cylinder 9 of bolt 4, this means preferably comprising a hollow extension 17 and a second projection 18 spaced rearwardly therefrom. Pinion 19, 15 housed in hollow extension 17, is provided with an axially arranged pin 20 extending through an opening in the rear wall of extension 17 and through extension 18. A portion of the pin 20, which normally lies 20 between the two projections 17 and 18, may, if desired, be suitably squared so that a lever 21 mounted therein may turn the pin 20 and thereby actuate pinion 19. The pinion 19 carries, on a portion of its periphery, 25 a series of gear teeth 22 adapted to engage with corresponding gear teeth or serrations 23 provided on the cylindrical portion 9 of bolt 4 so that when the lever 21 is moved the pinion 19 may rotate the bolt 4. A recess 24 30 is provided along the axial center line of pinion 19 to receive the projecting end of pin 7, above described, whereby the pinion 19 is interiorly supported in certain positions of the bolt in the receiver. To prevent entrance 35 of dirt or foreign matter into the gear teeth of the pinion 19, a gear guard in the form of a thin washer 5 is secured to spindle 7 in a position to cooperate with the forward open end of hollow extension 17 when the 40 bolt is in firing position in the receiver.

26 indicates a spring pressed pawl carried in bolt sleeve 16 to engage with lug 12 in certain positions of the bolt 4 with respect to the sleeve 16 and thereby prevent 45 relative rotation of these parts. To release the pawl 26, I have provided projection 8 hereinabove described, which is so positioned that when the bolt 4 is in firing position in the receiver 3, the pawl 26 engages with projection 8 and is disengaged from lug 12 so that the bolt may be freely rotated.

When for example a Springfield rifle of the model of 1903 type is to be altered in accordance with my invention, the only 55 parts which require changing or alteration are the receiver and bolt parts. The receiver may be made suitable for my purpose by cutting away a portion of the ordinary projection on the left side to form projection 5. 60 In so doing, projection 8 may be formed and the receiver suitably altered as by removal of a portion of the metal immediately to the rear of projection 5 and on the top of the receiver 3 to accommodate the breech bolt sleeve 16.

The bolt 4 may be employed substantially in its entirety but it is necessary to provide a sleeve 16 of the form hereinabove described. The lever in the 1903 model type of Springfield rifles, corresponding to operating lever 21 shown herein, may be removed entirely, but I prefer to sever it from the bolt so as to leave a lug 26 integral with lug 12 and of sufficient height and dimensions to engage with the cylindrical part 3^b 75 of the receiver and thereby enable the bolt to perform all of its normal functions and movements in the receiver traceable to the shank of the operating lever before the same is severed. 80

It will be observed that I have provided a bolt for a fire arm, particularly of the Springfield and Mauser bolt operated repeating rifle types which can be operated from the left side and is therefore easier 85 for a lefthanded person to employ, and furthermore that the device by which this has been accomplished are extremely simple and can be readily applied to an existing fire arm without extensive alterations or prohibitive cost. It will further be noted that I 90 provided a pinion operated bolt which may be actuated from the left side of the gun.

Having thus described my invention so that those skilled in the art may be able to practice the same, what I desire to secure by Letters Patent is defined in what is claimed, it being understood, however, that various changes or alterations may be made in the structure hereinabove described 100 without departing from the spirit and scope of my invention.

What is claimed is:

1. A bolt operated fire arm comprising in combination a magazine, means to eject 105 shells therefrom on the right side of the fire arm, a bolt receiver, a bolt rotatably mounted therein and means on the left side of the said bolt for rotating the bolt in the receiver.

2. A bolt operated fire arm comprising in combination a magazine, means to eject shells therefrom on the right side of the fire arm, a bolt receiver, a bolt rotatably mounted therein and means on the left side of the 115 said bolt for rotating the bolt in the receiver, said means comprising a pinion and an operating lever.

3. A bolt operated fire arm comprising in combination a magazine, means to eject 120 shells therefrom on the right side of the fire arm, a bolt receiver, a bolt slidably and rotatably mounted therein, and means on the left side of said bolt comprising a pinion and lever pivoted to the bolt for actuating the bolt longitudinally and rotatably.

4. A bolt operated fire arm comprising in combination a magazine, means to eject 125 shells therefrom on the right side of the fire arm, a bolt receiver, a bolt movably mounted therein, a pinion housing carried by the 130

bolt, a pinion in the housing operatively engaging the bolt, and means on the left side of said bolt for actuating the said pinion.

5. A bolt operated fire arm comprising in combination a magazine, means to eject shells therefrom on the right side of the fire arm, a bolt receiver, a bolt movably mounted therein, a pinion housing carried by the bolt, a pinion in the housing operatively engaging the bolt, and a lever on the left side of said bolt and secured to the said pinion.
6. A bolt operated fire arm comprising in combination a magazine, means to eject shells therefrom on the right side of the fire arm, a bolt receiver, a bolt movably mounted therein, having gear teeth on its exterior surface, a pinion housing carried by the bolt, a pinion in the housing operatively engaging the gear teeth in the said pinion and means on the left side of said bolt for actuating the pinion.

7. A bolt operated fire arm comprising in combination a bolt receiver, a bolt movably mounted therein, a pinion housing carried by the bolt on the left side thereof, a pinion in the housing operatively engaging the bolt and means for actuating the said pinion.

8. A bolt operated fire arm comprising in combination, a breech bolt receiver having a lateral extension on its left side, a spindle projecting rearwardly from the extension and in substantial alignment with the longitudinal axis of the receiver, a breech bolt movably mounted in the receiver and provided adjacent to its rear end with gear teeth extending longitudinally thereof, a breech bolt sleeve having a hollow extension on its left side, a pinion housed in said extension and operatively engaging the bolt, said pinion having an axial recess, the said spindle being adapted to extend into the recess to support the pinion internally when the pinion is rotated, means for moving the breech bolt in the receiver, and means for locking the bolt against rotational movement.

9. A bolt operated fire arm comprising in combination a breech bolt receiver having a lateral extension on its left side, a spindle projecting rearwardly from the extension and in substantial alignment with the longitudinal axis of the receiver, a breech bolt movably mounted in the receiver and provided adjacent to its rear end with gear teeth extending longitudinally thereof, a breech bolt sleeve having a hollow extension on its left side, a pinion housed in said extension having an axial recess, the said spindle being adapted to extend into the recess to support the pinion internally when the pinion is rotated, means for moving the breech bolt in the receiver, comprising a lever secured to the pinion to rotate the same, and means for locking the bolt against rotational movement.

10. A bolt operated fire arm comprising

in combination, a breech bolt receiver having a lateral extension on its left side, a spindle projecting rearwardly from the extension and in substantial alignment with the longitudinal axis of the receiver, a breech bolt movably mounted in the receiver and provided adjacent to its rear end with gear teeth extending longitudinally thereof, a breech bolt sleeve having a hollow extension on its left side, a pinion housed in said extension and having an axial recess, the said spindle being adapted to extend into the recess to support the pinion internally when the pinion engages the gear teeth on the breech bolt, for moving the breech bolt in the receiver and means for locking the bolt against rotational movement, comprising a spring pressed pawl carried by the breech bolt sleeve and engaging the bolt.

11. A bolt operated fire arm comprising in combination a breech bolt receiver having a lateral extension on its left side, a spindle projecting rearwardly from the extension and in substantial alignment with the longitudinal axis of the receiver, a breech bolt movably mounted in the receiver and provided adjacent to its rear end with gear teeth extending longitudinally thereof, a breech bolt sleeve having a hollow extension on its left side, a pinion housed in said extension and operatively engaging the bolt, said pinion having an axial recess, the said spindle being adapted to extend into the recess to support the pinion internally when the pinion is rotated, means for moving the breech bolt in the receiver, and means for locking the bolt against rotational movement comprising a spring pressed pawl carried by the breech bolt sleeve and engaging the bolt, the said pawl being disengaged from locking engagement with the bolt by contact in certain of its positions with the said receiver.

12. A bolt operated fire arm comprising in combination a breech bolt receiver having a lateral extension on its left side, a spindle projecting rearwardly from the extension and in substantial alignment with the longitudinal axis of the receiver, a gear guard on the said spindle, a breech bolt movably mounted in the receiver and provided adjacent to its rear end with gear teeth extending longitudinally thereof, a breech bolt sleeve having a hollow extension on its left side, a pinion housed in said extension and operatively engaging the bolt, said pinion having an axial recess, the said spindle being adapted to extend into the recess to support the pinion internally, means for moving the breech bolt in the receiver, and means for locking the bolt against rotational movement.

13. A bolt operated fire arm comprising in combination a breech bolt receiver having a rearward top extension and lateral left side projections, a spindle in the side pro-

jection carrying a cut-out lever between the projections, and extending rearwardly of the rear projection, a gear guard on the rearward extension of the said spindle, a breech bolt movably mounted in the said receiver and having gear teeth, a breech bolt sleeve having a hollow extension on its left side the wall of which is cut away adjacent to the bolt to expose the said gear teeth on the bolt, a pinion in the said hollow extension engaging with the said gear teeth and having a central recess to receive the end of said spindle, a lever secured to the pinion, a spring pressed pawl in the breech bolt sleeve lockingly engaging the bolt, the said pawl being adapted to engage the said rearward

top extension on the receiver in certain positions of the bolt in the receiver and being thereby withdrawn from locking engagement with the bolt.

20

14. A breech bolt for a fire arm of the class described comprising in combination a bolt having gear teeth on its exterior surface near the rear end thereof, a cocking piece, a sleeve carrying a pinion on the left side of said bolt and having gear teeth engaging the said gear teeth on the bolt, and a lever secured to the pinion to rotate the latter in the sleeve.

25

In testimony whereof I hereunto affix my signature this 11 day of Feby., 1924.

WILLIAM E. DUTE.
